UNITED STATES PATENT OFFICE.

ROLLIN N. CONWELL, OF BLOOMFIELD, NEW JERSEY.

ELECTRICAL METHOD AND APPARATUS.

Application filed August 21, 1922. Serial No. 583,223.

This invention relates to electrical methods and apparatus, and with regard to certain more specific features, to methods and apparatus for use in connection with alternating 5 currents.

The present invention relates to subject matter analogous to my Patents 1,508,360, 1,508,361, 1,508,362 and 1,508,363, all dated September 9, 1924.

10 Among the several objects of the invention may be noted the provision of inexpensive and durable electrical apparatus for effecting the various results hereinafter indicated, utilizing inductive action; and the provision 15 of simple and reliable methods of attaining such results. Other objects will be in part obvious and in part pointed out hereinafter.

This invention differs from the inventions set forth in the patents above mentioned, 20 among other things, by the fact that means is provided for causing operation of the relay on a ratio differential basis. For example, with a 2½% setting, the relay will operate when the current in one winding exceeds the current in the other winding by 25 2½%. The relay is preferably provided with a plurality of ratio or percentage taps, so that the user can select the percentage at which he wishes the relay to operate.

30 The invention accordingly comprises the features of construction, steps and sequence of steps, combinations of elements and arrangements of parts, which are exemplified in the description hereinafter in connection 35 with the accompanying drawings, and the scope of the application of which will be indicated in the following claims.

In the accompanying drawings, in which are illustrated diagrammatically several of 40 various possible embodiments of the invention,

Fig. 1 is an elevation of one form of apparatus, showing normal conditions;

Fig. 2 is a plan of the parts shown in 45 Fig. 1, excluding the connections;

Fig. 3 is a view similar to Fig. 1, showing circuit conditions upon reversal of current at one source;

Fig. 4 is a view similar to Fig. 1, showing 50 circuit conditions when the currents at the sources are of unequal magnitude but not relatively reversed;

Fig. 5 is an elevation of a modified form 55 of apparatus, showing normal circuit conditions;

Fig. 6 is a view similar to Fig. 5, showing circuit conditions upon reversal of current at one source;

Fig. 7 is a view similar to Fig. 5, showing circuit conditions when the currents at the 60 sources are of unequal magnitude but not relatively reversed; and

Fig. 8 illustrates switch gear utilizing the constructions shown in Figs. 1 to 7.

Similar reference characters indicate corresponding parts throughout the several views of the drawings.

Referring now more particularly to Fig. 1, there are illustrated at SM, S8 and S9 three terminals adapted to be connected to two 70 sources of alternating current, which may be derived from one or more circuits; transformers T1, T5 adapted to be energized from said sources as hereinafter described; a primary winding X1, X6—X7 for each of the 75 respective transformers; a leg or pole piece or core element L1, L5 for each of said respective transformers; and a secondary winding Y1, Y5 for each of said respective transformers.

80 The transformer fluxes are due to the magneto-motive forces of the ampere turns of the primary and secondary windings of the respective transformers.

Another flux is induced by current passing 85 through two other windings OW1, OW5 connected to the respective secondary windings Y1, Y5 of the transformers. These two other windings are each wound upon two legs OL2, OL4. The net flux, if other than zero, 90 operates with the transformer fluxes. These several fluxes induce electric currents in one or more conductors, for some useful purpose. In the present embodiments of the invention the conductor is a movable element, to wit, 95 a disc G pivoted as at 10 to one side of the plane of the laminated core C. The disc is driven by the vectorial sum of the forces acting upon it, that is, the resultant force arising from the reaction of the resultant flux and the flux caused by the electric currents induced thereby in the driven element G.

100 The driven element G may simply allow an observer to determine its position and/or direction of movement, as in synchronizers. 105 Or the driven element may deliver mechanical power for power purposes, or run a totalizer or operate a pointer or recording device (stylus or the like) or contacts M—N or the like.

In the present instance the apparatus is illustrated as a relay, and the disc G normally tends to rotate in one direction. Upon a reversal of current at one source, the disc tends to rotate in the other direction, retarded if desired by one or more drag magnets DM (Fig. 2) and the torque developed is determined by the magnitude of the abnormality that causes the torque. Such torque may be used for any of the several purposes above named, for which such torque may be suitable.

Normal condition.—In tracing the several currents and fluxes during normal condition, assume one source of power to be connected across the terminals SM, S8 and the other to be connected across the terminals SM, S9, with the currents from two sources equal and in phase, and the connections such that the currents from the two sources circulate. A connection of this type is illustrated in Fig. 8 hereinafter described. Assume the ampere turns in the two primary sections X6, X7 equal (connection 20). No current flows through primary X1 because its two terminals are connected to equipotential points. There is thus no current in secondary Y1, and none in other winding OW1. Current in primary sections X6—X7 induces in secondary Y5 a current that energizes the other winding OW5. It will be seen by tracing the circuits, that a traveling field is formed, tending to move the disc in the same direction as during abnormal condition I.

Fig. 3.
35 *Abnormal condition I, caused by reversal of current at one source.*—Upon a reversal of current at one source such as SM—S8, the currents from the two sources do not circulate but oppose one another. Primary X1 is thus energized, inducing current in secondary Y1, which in turn energizes the other winding OW1. The current in the latter winding produces polarities at the other legs OL2, OL4 opposite to the polarities produced at said legs by current in the other winding OW5 (normal condition). The primary sections X6—X7 oppose and ordinarily neutralize one another, so that there is no current in secondary Y5 and none in the other winding OW5. The primary X1 is so wound with respect to the primary sections X6—X7 that upon reversal of current at one source the traveling field produced by the several fluxes moves in the opposite direction to its direction during normal condition, thereby tending to rotate the disc in the direction opposite to the direction in which it tends to rotate during normal condition.

Fig. 4.

Abnormal condition II, caused by relative increase of current at one source without reversal.—When the current at one source such

as S9 increases relatively to the current at the other source, the currents at the two sources continue to circulate but their common terminal SM has a potential that is not midway between the potentials of terminals S8 and S9. Primary X1 is thus energized, inducing current in secondary Y1, which in turn energizes other winding OW1. Current in primary sections X6—X7 induces in secondary Y5 a current that energizes other winding OW5. Primary X1 has preferably a much larger number of ampere-turns than primary X6—X7. The current in winding OW1 is therefore of greater magnitude than the current in the other winding OW5, and hence the net flux at the other legs OL2, OL4 is of the same polarity as during abnormal condition I. It will be seen by tracing the circuits, that a traveling field is formed, tending to move the disc in the same direction as during abnormal condition I.

Similarly, an increase of current at S8 relative to S9 causes the disc to tend to rotate in the same direction as during abnormal condition I. For brevity, the circuit conditions are not here shown in detail.

Résumé.—The relay disc thus tends to move in one direction during normal condition. Upon a reversal of current at either source of power (abnormal condition I) the relay tends to move in the other direction. Upon an increase of current at either source of power, without reversal (abnormal condition II) the relay tends to move in the same direction as during abnormal condition I.

Figs. 1-4 modified to have primaries X6 and X7 unequal.

(See connections 21 and 22 in Fig. 1).

The above construction and operation are similar to those above described, except that there is normally current in primary X1, secondary Y1 and other winding OW1. It will be seen by tracing the circuits that this alters the magnitude of the restraining torque exerted by reason of current in primary sections X6—X7: in other words, it alters the amount of "bias."

Fig. 5.

Construction.—The relay shown in Fig. 5 is constructed in similar manner to the relay in Figs. 1 to 4 except that the other windings OW1, OW5 are replaced by another winding OW, and the secondary windings Y1, Y5 are connected to circulate during normal condition and to oppose upon a reversal of current in either of said secondary windings. The other winding OW is connected to normally equipotential points of the circuit that includes the secondary windings Y1, Y5.

Normal condition.—In tracing the several currents and fluxes during normal condition, assume the sources to be connected as in Fig.

1, with the currents from the two sources equal and in phase, and the connections such that the currents from the two sources circulate. A connection of this type is shown in Fig. 8, hereinafter described. Assume the 5 ampere turns in the two primary sections X₆, X₇ equal. No current flows through primary X₁ because its two terminals are connected to equipotential points. There is thus no current induced in secondary Y₁. The 10 current in primary sections X₆—X₇ induces in secondary Y₅ a current that energizes other winding OW. It will be seen by tracing the circuits that a traveling field is formed, tending to move the disc in one direction.

Fig. 6.

Abnormal condition I, caused by reversal of current at one source.—Upon a reversal of 20 current at one source, such as S_M, S₈, the currents from the two sources do not circulate but oppose one another. Primary X₁ is thus energized, inducing current in secondary Y₁. The primary sections X₆, X₇ 25 oppose and ordinarily neutralize one another so that there is no current induced in secondary Y₅. The current in secondary Y₁ energizes the other winding OW in a direction opposite to the direction during normal condition. The primary X₁ is so wound with 30 respect to the primary sections X₆—X₇ that upon reversal of current at one source the traveling field produced by the several fluxes moves in the opposite direction to its 35 direction during normal condition, thereby tending to rotate the disc in the direction opposite to the direction in which it tends to rotate during normal condition.

Fig. 7.

Abnormal condition II, caused by relative increase of current at one source, without reversal.—When the current at one source such as S₉ increases relatively to the current 40 at the other source, the currents at the two sources continue to circulate but their common terminal S_M has a potential that is not midway between the potentials of terminals S₈ and S₉. Primary X₁ is thus energized, inducing current in secondary Y₁. Current 45 in primary sections X₆—X₇ induces current in secondary Y₅. The former current is of greater magnitude than the current induced in secondary Y₅. The terminals of other 50 winding OW₁ thus have the same polarities as during abnormal condition I. It will be seen by tracing the currents, that a traveling field is formed, tending to move the disc in the 55 same direction as in abnormal condition I.

Résumé.—The relay disc thus tends to move in one direction during normal condition; and in the other direction upon a reversal of current at either source of power (abnormal condition I) or upon a relative in-

crease of current at one source of power 65 without reversal (abnormal condition II).

Figs. 5 to 7 modified to have primaries X₆ and X₇ unequal.

(See connections 21 and 22 in Fig. 5). 70 The construction and operation are similar to those above described, except that there is normally current in primary X₁ and therefore induced current in secondary Y₁. This alters the restraint due to current in primary 75 section X₆—X₇.

Fig. 8.

Construction.—In Fig. 8 three relays of the type shown in Figs. 1 to 4 or Figs. 5 to 7 are shown, connected to operate as a directional current switch gear, with a three-phase grounded-neutral generator O. On the neutral side of each armature winding is a current transformer CN, one side of which is connected to the left terminal of the corresponding relay and the other to the right terminal of the relay. On the bus side of each transformer winding is a current transformer CL, one side of which is connected to the left terminal of the relay for that phase and the other to the middle terminal of the same relay. The several windings are so connected that during normal operation the currents in each set of transformers CL, CN circulate, corresponding to the normal condition of the relay as described above; whereas upon a relative reversal of current in the transformers CL, CN of any phase (caused, for example, by a fault in the armature winding of that phase) the relay for that phase 90 operates as described above under abnormal condition I and trips the circuit-breaker CB. Relative increase of current in one current transformer with respect to the other current transformer of the same phase without reversal, causes action of the relay as indicated above in connection with abnormal condition 95 II.

In general.

If during normal condition the two sources of power of the relay are out of phase with one another by an acute angle, the relay still tends to rotate in the direction corresponding to the normal condition described above. 110 Similarly upon a reversal (abnormal condition I) or inequality of currents (abnormal condition II) that does not cause an exact 180-degree relationship between the two currents, the relay tends to rotate in the same 115 direction as if the currents were 180 degrees apart.

The above also applies to embodiments of the invention in apparatus other than relays, that is, an acute-angle out-of-phase relation 120 between the currents of the two sources does not cause the device to operate other than as described above under normal condition or

abnormal condition II respectively; and during reversal, when the reversal is not exactly 180 degrees, the device nevertheless tends to operate in the same manner as when the currents are 180 degrees apart.

In the system shown in Fig. 8, the relays may each be provided with a movable and two fixed contacts, so that the relay closes one circuit during normal condition and another 10 circuit during reversal. The illustrated system is merely representative of apparatus protection, and of various other classes of systems to which the present invention, in certain of its aspects, is applicable.

15 From the above it will be seen that the several objects of the invention are attained and other advantageous results achieved.

As many modifications of the embodiments above illustrated might be made without departing from the spirit or scope of the present invention, it is intended that the above description and accompanying drawings and claims shall be interpreted as illustrative and not in a limiting sense.

25 I claim:

1. In apparatus of the class described, in combination, a plurality of transformers, primary and secondary windings therefor, the primary windings adapted to be energized 30 from a circuit including a plurality of sources of power, one primary being connected to said sources and to a point on the other primary, and the other primary being connected in said circuit, and means cooperating with said 35 secondary windings for producing fluxes coacting with the transformer fluxes to set up traveling magnetic fields.

2. In apparatus of the class described, in combination, a plurality of transformers, primary and secondary windings therefor, the primary windings adapted to be energized 40 from a circuit including a plurality of sources of power, connected to one another for circulation and opposition, one primary being connected to said sources and to a point on the other primary, and means cooperating with said 45 secondary windings for producing fluxes coacting with the transformer fluxes to set up traveling magnetic fields.

3. In apparatus of the class described, in combination, a plurality of transformers, primary and secondary windings therefor, the primary windings adapted to be energized 50 from a circuit including a plurality of sources of power, connected to one another for circulation and opposition, one primary being connected to said sources and to a point on the other primary, and the other primary being connected in said circuit, and means co- 55 operating with said secondary windings for producing fluxes coacting with the transformer fluxes to set up traveling magnetic fields.

4. In apparatus of the class described, in 60 combination, a plurality of magnetically co-

acting transformers, primary and secondary windings therefor, the primary windings adapted to be energized from a circuit including a plurality of sources of power, connected for circulating currents during normal operation, one primary being connected to said sources and to an intermediate point on the other primary, and the other primary being connected in said circuit, and means cooperating with said secondary windings for producing fluxes coacting with the transformer fluxes to set up traveling magnetic fields.

5. In apparatus of the class described, in combination, a plurality of transformers, primary and secondary windings therefor, a 70 circuit adapted to be connected to two sources of power for circulating currents during normal condition, one of said primaries being connected to said sources and to an intermediate point on the other primary, the other primary being connected in said circuit, means cooperating with said secondary windings for producing fluxes with the resultant of the transformer fluxes, means for combining said transformer fluxes and said other 75 fluxes to produce traveling fields, and a member responsive to said traveling fields.

6. In apparatus of the class described, in combination, a plurality of transformers, primary and secondary windings therefor, the 80 primary windings adapted to be energized from a circuit including a plurality of sources of power, one primary being connected to said sources and to a midpoint on the other primary, and the other primary being connected in said circuit, and means cooperating with said secondary windings for producing fluxes 85 coacting with the transformer fluxes to set up traveling magnetic fields.

7. In apparatus of the class described, in combination, a plurality of transformers, primary and secondary windings therefor, the primary windings adapted to be energized 90 from a circuit including a plurality of sources of power, one primary being connected to said sources and to a non-mid-point on the other primary, and the other primary being connected in said circuit, and means cooperating with said secondary windings for producing fluxes 95 coacting with the transformer fluxes to set up traveling magnetic fields.

8. A directional current switch gear comprising a plurality of sources of current connected in a circuit for circulation during normal operation and for opposition upon relative reversal of current in said sources, a relay having a winding in said circuit and a winding connected to said sources and to an intermediate point on the first winding, and means whereby said windings cause traveling fields tending to cause movement of the relay in one direction during circulation and in another direction during opposition of the currents in said sources.

9. In apparatus of the class described, in 130

- combination, a plurality of transformers, primary and secondary windings therefor, a circuit adapted to be connected to two sources of power for circulating currents during normal condition, one of said primaries being connected to said sources and to an intermediate point on the other primary, the other primary being connected in said circuit, opposing windings connected with the respective secondary windings for producing fluxes with the resultant of the transformer fluxes, means for combining said transformer fluxes and said other fluxes to produce traveling fields, and a member responsive to said traveling fields.
10. In apparatus of the class described, in combination, a plurality of transformers, primary and secondary windings therefor, a circuit adapted to be connected to two sources of power, one of said primaries being connected to said sources and to an intermediate point on the other primary, the other primary being connected in said circuit, the secondaries being connected in a circuit, and a winding connected across said circuit and adapted to produce fluxes with the resultant of the transformer fluxes, and means for combining said transformer fluxes and said other fluxes to produce traveling fields.
20. 11. In apparatus of the class described, in combination, a plurality of transformers, primary and secondary windings therefor, a circuit adapted to be connected to two sources of power for circulating currents during normal condition, one of said primaries being connected to said sources and to an intermediate point on the other primary, the other

primary being connected in said circuit, the secondaries being connected in a circuit, and a winding connected across said circuit and adapted to produce fluxes with the resultant of the transformer fluxes, means for combining said transformer fluxes and said other fluxes to produce traveling fields, and a member responsive to said traveling fields.

12. The method of inducing currents in a conductor, which comprises producing magnetically coacting fluxes from a plurality of sources of power connected normally for circulation but for opposition upon relative reversal of current in said sources, producing from the said fluxes fluxes in quadrature with the first fluxes, and causing said several fluxes to combine to form one or more traveling fields inducing currents in said conductor.

13. In apparatus of the class described, in combination, a plurality of transformers, primary and secondary windings therefor, the primary windings adapted to be energized from a circuit including a plurality of sources of power, one primary being connected to said sources and to a point on the other primary, the latter connection being movable and the other primary being connected to said circuit and means cooperating with said secondary windings for producing fluxes coacting with the transformer fluxes to set up traveling magnetic fields.

In testimony whereof, I have signed my name to this specification this fourteenth day of August, 1922.

ROLLIN N. CONWELL.
